J. W. McFARLAND

RADIATOR

Filed July 2, 1920

INVENTOR.

James W. McFarland

BY

Hazard E. Miller
ATTORNEY

UNITED STATES PATENT OFFICE.

JAMES W. MCFARLAND, OF LOS ANGELES, CALIFORNIA.

RADIATOR.

Application filed July 2, 1920. Serial No. 393,627.

To all whom it may concern:

Be it known that I, JAMES W. MCFARLAND, a citizen of the United States, residing at Los Angeles, in the county of Los Angeles and State of California, have invented new and useful Improvements in Radiators, of which the following is a specification.

This invention relates to radiators such as are employed in connection with internal combustion engines.

It is the object of the invention to provide a radiator comprising independent core sections which may be readily detached from and connected to the headers of the radiator.

The invention will be readily understood from the following description of the accompanying drawings, in which—

20 Figure 1 is a front elevation of a radiator constructed in accordance with the invention.

Fig. 2 is an enlarged longitudinal section on the line 2—2 of Fig. 1.

25 Fig. 3 is a detail section on the line 3—3 of Fig. 2.

Fig. 4 is an enlarged front elevation of one end of one of the radiator sections.

Fig. 5 is a transverse section on the line 30 5—5 of Fig. 2.

The radiator comprises usual upper and lower headers 1 and 2, preferably, substantially rectangular in cross section and extending the width of the radiator. A plurality of core sections 3 are arranged along side one another between the headers, these core sections being each provided with side plates 4 arranged to form a unitary structure of the respective core sections and also 35 adapted when the core sections are placed in juxtaposition between the headers to form additional radiating surfaces.

The core sections are provided with means for connecting the sections to headers 45 1 and 2 so that individual core sections may be readily removed and inserted in position. The connecting means at the respective ends of a core section is shown as a casting 5 consisting of angularly disposed sides 5^a and 5^b arranged to abut against the front of a header of the radiator and against the end of the core section respectively. The surface of a header against which the casting abuts is, preferably, inclined as shown at 6 and the abutting surface of the casting is similarly inclined as

shown at 7 with a gasket 8 interposed between said abutting surfaces. The outer surface of the side 5^a of the casting is provided with bosses 9 through which bolts 10 60 may be received for detachably connecting the casting to the radiator header. These bolts extend through the casting and through the header of the radiator and are threaded into suitable bosses 11 provided upon the interior surface of the header. When the casting is thus connected to the radiator header the side 5^b thereof is arranged to lie against the wall of the header, and said side of the casting is permanently secured to 65 the end of a core section as by soldering. The side 5^b, preferably, lies flush against the end of the core section with the side plates 4 of the core section, preferably, extending along side of the edges of the casting. 70

A port 13 is provided in the inclined walls 6 of the radiator headers in alinement with each of the castings 5, and the side 5^a of each casting is provided with a port 14 in its inner surface in alinement with port 13. The port 14 communicates with the hollow interior 15 of the side 5^a of the casting, which hollow interior communicates with a recess 16 provided in the outer 80 surface of the side 5^b of the casting. This recess communicates with the water channels through the core section to which the casting is secured, said casting being secured to the core section at its edge 17 surrounding the recess 16. 85

It will be observed that both the hollow interior 15, and recess 16, of a casting 5, extend inwardly from the outer surface of said casting, and are of such conformation 90 that in casting the same, no interior core is necessary in the mold employed for the casting operation. The mold will simply be provided with suitable protuberances upon its surface arranged to form the openings through the casting, the casting being of such shape that it may be readily removed from the mold. 100

I have thus provided an extremely simple construction which will be inexpensive 105 to manufacture, due to the simplicity of the mold employed, the castings when formed, being adapted to be permanently secured to the respective ends of a core section to provide a removable structure 110 detachably secured by bolts 10 to the radiator headers.

Various changes may be made without departing from the spirit of the invention as claimed.

What is claimed is:

- 5 1. A radiator comprising headers having one of their vertical walls inclined and formed with an opening, bosses formed interiorly of the headers adjacent to said openings, core sections between the headers, and connecting members at the ends of the core sections, each of said connecting members having a horizontal portion communicating with the adjacent end of the corresponding core section and a vertical portion 10 tapered and adapted to contact with the inclined portion of the corresponding headers, said vertical portion being in communication with the horizontal portion and with the opening to the corresponding header, bosses formed on the connecting members, and fastening members extending through the bosses of the connecting members and of said header for securing the connection members to the headers.
- 15 2. A radiator comprising headers having one of their vertical walls inclined and formed with openings, bosses formed interiorly of the headers adjacent to said openings, and disposed in parallelism with

said walls, core sections between the headers, 30 and connecting members at the ends of the core sections, each of said connecting members having a horizontal portion communicating with the adjacent end of the corresponding core section and a vertical portion 35 tapered and adapted to contact with the inclined portion of the corresponding headers, said vertical portion being in communication with the horizontal portion and with the opening to the corresponding header, tapered bosses formed on the connecting members and having outer faces disposed in parallelism with the first bosses, and fastening members extending at right angles through the bosses of the connecting members 40 and of said header for securing the connection members to the headers.

3. A radiator comprising headers, core sections, and connecting members at the ends of said core sections, each connecting member having a side abutting against the inclined side of a header, said abutting side being correspondingly inclined, and means for detachably connecting said sides to said headers.

In testimony whereof I have signed my name to this specification.

JAMES W. McFARLAND.
